UNITED STATES PATENT OFFICE.

ANVY H. MILLER, OF MINBURN, IOWA.

GRADING AND LEVELING MACHINE.

1,142,114.

Specification of Letters Patent.

Patented June 8, 1915.

Application filed November 2, 1914. Serial No. 869,747.

To all whom it may concern:

Be it known that I, ANVY H. MILLER, a citizen of the United States, residing at Minburn, in the county of Dallas and State of 5 Iowa, have invented certain new and useful Improvements in Grading and Leveling Machines, of which the following is a specification.

This invention relates to improvements in 10 grading and leveling machines and one of the objects of the same is to provide an improved machine of this character, which may be readily converted from one form or shape into another according to the work to 15 be performed.

A further object is to provide an improved machine of this character which will be simple, durable and cheap in construction, and effective and efficient in operation, 20 and one which may be readily converted when desired.

Other and further objects will appear from the following specification and claims taken in connection with the accompanying 25 drawings in which—

Figure 1 is a top plan view of an improved machine of this character, constructed in accordance with the principles of this invention. Fig. 2 is a top plan view of the 30 machine showing the same converted or adjusted into another form. Figs. 3 and 4 are detail views partly in elevation and partly in section of one of the scraper supports and showing the scraper in different positions. 35 Fig. 5 is a top plan view of the machine showing the same converted into still another form. Fig. 6 is a detail sectional view taken on line 6—6, Fig. 5. Fig. 7 is a side elevation of Fig. 5. Fig. 8 is a rear elevation of the scrapers and the intermediate 40 holding means for the scrapers.

Referring more particularly to the drawings and in the present form of the invention, the numeral 10 designates generally a 45 supporting truck arranged at the front end of the machine and to which truck sectional beams are pivotally connected by means of the king pin 11 and these beams are of sectional construction, and respectively comprise the sections 12—13, 14—15, 16—17, 50 18—19, 20—21, connected to the king pin 11, so as to be laterally adjusted.

Each of the beams is here shown as com-

prising two sections, one of the sections being provided with a tongue 22 and the other 55 with a groove 23 into which the tongue projects and the beams are provided with a series of apertures or openings 24, 25, (see Figs. 7, 3 and 4), for the reception of the fastening devices 26^a by means of which the 60 respective sections of the beams are held together so as to be adjustable with relation to each other, thereby rendering it possible to lengthen or shorten the beams as desired.

Pivotaly connected at the rear extremity 65 of each of the sections, 13, 15, 19 and 21, is an upright 26, which may be of any desired height, and a brace 27 preferably in the form of a bifurcated member is provided and stands astride of each of the respective 70 sections of each of the beams, and this brace 27 is connected by means of a fastening device 28 and a series of apertures 29 in the beam sections to the respective beams at one end and is connected by means of a fastening device 30 to the respective uprights 26, so that the angle of the uprights with respect to the vertical may be varied by removing the fastening device 28 and adjusting that end of the brace longitudinally of 75 the beam and then reinserting the fastening device 28 into the respective apertures 29.

Connected with the section 17 of the intermediate beam is an arched shaped member 80 preferably comprising the sections 31, 32 pivotally secured to the beam section by means of connecting members 33, 34, and 35, although this arched shaped member may if desired be constructed of a single piece. Braces 36 are connected with the beam section 85 17 and also with the sides of the arched shaped member 31, 32.

Scraper blades 37, 38 are provided and are constructed of any desired or suitable material, and are so shaped that one of the 90 longitudinal edges thereof will be curved laterally as at 39 and sockets 40, 41, 42 are provided on the scraper 37 while similar sockets 43, 44, 45 are provided on the scraper 38. These sockets having openings 95 extending entirely therethrough for a purpose to be set forth.

The uprights 25 which are connected with the beam sections 19, 21 are adapted to enter the sockets 41, 40 of the scraper 37 while 100 105 the upright constituted by the side or mem-

ber 32 of the arched shaped member is adapted to enter the socket 42, (as shown in Fig. 1). The other side 31 of the arched shaped member is adapted to enter the socket 45 of the scraper 38 while the uprights of the beam section 15, 13 are adapted to respectively enter the sockets 44, 43 on the scraper 38, and thereby hold the ends of the scrapers 37, 38 in close proximity to each other as shown in Fig. 1 to adapt the machine to one form of grading. The uprights and the scrapers are held in this position in any desired or suitable manner, such as by means of fastening devices 46, 15 entering the sockets and engaging the respective uprights. A seat 47 supported by members 48, 49 may be provided and these members 48, 49 are connected respectively by clips 50, 51 with the beams comprising the 20 sections 18-19 and 14-15.

The beams comprising the sections 12-13 and 14-15 are arranged at a lower elevation than the remaining beams, so as to be shifted in a manner to be hereinafter described, and 25 the element 48 of the seat support is of a length greater than the element 48 in order to compensate for this difference of the elevation of the two sides of the machine.

The scrapers 37, 38 may be attached to the 30 respective uprights in any manner, that is to say, with the curved portion of the blade lowermost as shown in Fig. 3, or the blades may be removed from the respective uprights and reversed, so that the curved edge 35 will be uppermost and the straight edge lowermost as shown in Fig. 4, the sockets on the blades having the openings extending through the opposite ends of the sockets, being provided for this purpose.

40 If desired, a roller 52 may be provided and attached to the machine by means of a tongue 53, which engages a pin or projection 54 connected with a clip 55 and which clip is secured to the section 17 of the intermediate beam, so that the roller will be 45 preferably arranged in the rear of the intermediate edges of the scraper. A foot rest 56 may also be provided for the operator, if desired. The scraper blade 37 is also provided with a socket 57 while the scraper blade 38 is also provided with a socket 58, and these sockets are arranged adjacent the inner edges of the respective scrapers and are adapted to receive the respective uprights of the arched shaped members 32, 31 55 when they are removed from the sockets 42, 45 so that the blades may be shifted with respect to each other from the position shown in Fig. 1 to the positions shown in Fig. 2, 60 thereby forming an opening between the inner edges of the blades, and the beams connected with the outer edges of the respective blades may be adjusted to vary the angle of inclination of the blades longitudinally of 65 the machine so that they may be positioned

as shown in Fig. 2. In this form of the invention, the roller 52 will follow the opening between the inner edges of the blade.

When it is desired to convert the machine into the form shown in Figs. 5 and 7, the inner edge of the blade 38 is detached from the arch shaped member, and the lengths of the beams comprising the sections 12-13 and 14-15 are varied or shortened. Inasmuch as the latter beams are of a lower elevation than the remaining beams, the scraper blade 38 and the connected beams may be then swung under the remaining beams into the positions shown in Figs. 5 and 7. In this position and in order to support the end 75 of the blade 38 which formerly constituted the innermost end thereof is provided another beam, arranged adjacent the beam comprising the sections 20-21 and this additional beam is also pivotally connected to 80 the king pin 11 and comprises the sections 59, 60, constructed in a manner similar to the remaining beams. An upright 61 is connected with the beam section 60 and is adjustably held in position by means of a brace 90 62, and this upright 61 is adapted to enter the socket 45, to hold the blade in its adjusted position. When the machine is in this form, the blades 37, 38 may be arranged in any position with respect to each other, 95 that is the curved edges may be arranged uppermost if desired, or adjacent the ground, the blades may also be arranged to have the curved edges extending forwardly or rearwardly, or one forwardly or rearwardly according to the work to be performed. The blade 38 is also adapted to be raised and lowered with respect to the blade 37 so as to dump the dirt when desired. In order to accomplish this there is provided 100 an actuating lever, 63, which is pivotally supported preferably by the beam comprising the sections 20-21, and a segment 64 with which this lever 63 co-operates is also provided. This lever 63 is connected as at 105 65 with the beam comprising the sections 59-60, so that when the lever is actuated, this beam will be raised or lowered and consequently the end of the scraper which is attached thereto will be correspondingly adjusted. In order to raise and lower the other end of the beam 38, there is provided another lever 66, similar to the lever 63 and a segment 67 is provided for the lever 66. When the machine is in the form shown in 110 Fig. 5, the segment 67 and the lever 66 are connected with the intermediate beam comprising the sections 16-17 and the other end of the lever is connected as at 68 with the beam comprising the sections 12-13, so that 115 both of the levers 63, 66 will be conveniently positioned for the operator to permit the blade 38 to be raised or lowered at will.

When the machine is not used in the form 120 shown in Fig. 5, but is used in the form 125

shown in Figs. 1 and 2, the lever 66 and the segment 67 are detached from the beam comprising the sections 16, 17 and is laid back on the beam comprising the sections 12, 13 5 (as shown in Figs. 1 and 2) and is held there in any desired or suitable manner and serves as a weight for holding the end of the scraper down.

Obviously the beams may be connected 10 with the king bolt in any desired or suitable manner so as to permit of the desired adjustment, and the machine may be used with or without the roller as desired.

While there is shown and described, only 15 three modes of use of this machine, it is to be understood that the parts may be adjusted and positioned with respect to each other to adapt the machine for any work to be performed, and while the preferred 20 forms have been herein shown it is to be understood that many changes may be made in the details of construction and in the combination and arrangement of the several parts without departing from the spirit of 25 this invention.

What is claimed as new is:

1. A device of the character described, embodying an intermediate beam, a pair of beams arranged on each side thereof, a 30 scraper connected with each pair of beams, and means for detachably connecting the scrapers with the central beam, and embodying means for detachably connecting one end of each of the scrapers for holding the 35 scrapers in one position with respect to each other, the said side beams being longitudinally adjustable whereby the scrapers may be placed in tandem when the end of one of the blades is detached from the central beam.

40 2. A device of the character described, embodying an intermediate beam, a pair of beams arranged on each side thereof, a scraper connected with each pair of beams, means for detachably connecting the scrapers 45 with the central beam, and embodying means for detachably connecting one end of each of the scrapers for holding the scrapers in one position with respect to each other, said beams being of sectional construction longitudinally adjustable whereby the scrapers 50 may be placed in tandem when the end of one of the blades is detached from the central beam, said sectional construction of the beams also permitting the angular position 55 of the scrapers to be varied.

3. A device of the character described, embodying an intermediate beam, a pair of beams arranged on each side thereof, a scraper connected with each pair of beams, and means for detachably connecting the scrapers with the central beam and embodying means for detachably connecting one end of the scrapers with the said intermediate beam, one of said pairs of beams being arranged at a higher elevation than the other 60

pair of beams, said pairs of side beams being longitudinally adjustable, one pair of said beams adapted to be swung beneath the other pair when the respective scraper is detached from the said intermediate beam, 70 to position the scrapers one in advance of the other.

4. A device of the character described, embodying an intermediate beam, a pair of beams arranged on each side thereof, a 75 scraper connected with each pair of beams, and means detachably connecting one end of each of the scrapers with the said intermediate beam, one of said pairs of beams being arranged at a higher elevation than the other 80 pair of beams, whereby the latter may be swung beneath the former when the respective scraper is detached from the said intermediate beam, and the length of the respective beam is varied, to position the scrapers 85 one in advance of the other, said beams being constructed in sections adjustable with respect to each other to vary the length of the beams.

5. A device of the character described, embodying an intermediate beam, a pair of beams disposed on each side thereof, said pairs of beams being longitudinally adjustable to vary their length, scrapers connected with each of the said pairs of beams, means 90 detachably securing the inner ends of the scrapers to the said intermediate beam, one of said pairs of beams being so positioned with respect to the other pair of beams and the said intermediate beam, as to be movable thereunder, when the inner end of the respective scraper is detached from said intermediate beam, and the length of the respective beam is varied to position one of the scrapers in advance of the other, and an additional beam to which that end of the scraper which has been detached from the said intermediate beam is secured, when the scrapers are so positioned.

6. A device of the character described, 110 embodying an intermediate beam, a pair of beams disposed on each side thereof, scrapers connected with each of the said pairs of beams, means detachably securing the inner ends of the scrapers to the said intermediate 115 beam, one of said pairs of beams being so positioned with respect to the other pair of beams and the said intermediate beam, as to be movable thereunder, when the inner end of the respective scraper is detached from said intermediate beam, and the length of the respective beam is varied to position one scraper in advance of the other, and an additional beam to which that end of the scraper which has been detached from the 120 said intermediate beam is secured, when the scrapers are so positioned, said beams comprising adjustable sections whereby the length of each of the beams may be varied independently with respect to the others 125

when the scrapers are arranged one in advance of the other.

7. A device of the character described, embodying an intermediate beam, a pair of longitudinally adjustable beams disposed on each side thereof, scrapers connected with each of the said pairs of beams, one of said pairs of beams being so positioned with respect to the other pair of beams and the said intermediate beam, as to be movable thereunder, when the length of the respective beam is varied, to position one scraper in advance of the other, an additional beam to which one end of one of the scrapers is secured, when the scrapers are so positioned, and means for raising and lowering one of the scrapers with respect to the other when the scrapers are arranged one in advance of the other.

20 8. A device of the character described, embodying an intermediate beam, a pair of beams disposed on opposite sides thereof, said pairs of beams being adjustable laterally with respect to the intermediate beam, a pair of uprights connected with the said intermediate beam, and a scraper connected with each pair of beams, each of said scrapers provided with a plurality of sockets adjacent the inner ends thereof into which the respective uprights on the intermediate beams are adapted to be interchangeably seated, all of said beams comprising adjustable sections whereby the length of each of the beams may be varied independently with respect to each other.

35 9. A device of the character described, embodying an intermediate beam, a pair of beams disposed on opposite sides thereof, said pairs of beams being adjustable laterally with respect to the intermediate beam, a pair of uprights connected with the said intermediate beam, a scraper connected with each pair of beams, each of said scrapers provided with a plurality of sockets adjacent the inner ends thereof into which the respective uprights on the intermediate

beams are adapted to be interchangeably seated, and a truck supporting one end of the said beams.

10. A device of the character described, embodying an intermediate longitudinally adjustable beam, a pair of beams disposed on opposite sides thereof, said pairs of beams being also adjustable laterally with respect to the intermediate beam, an upright connected with the said intermediate beam, and a scraper connected with each pair of beams, one of said pairs of beams being disposed at a higher elevation than the other pair whereby the latter may be positioned under the former when the length of the respective beam is varied to position the one scraper in advance of the other, and means for raising and lowering one of the scrapers with respect to the other when the scrapers are thus positioned.

11. A device of the character described, embodying an intermediate beam, a pair of longitudinally adjustable beams disposed on opposite sides thereof, said pairs of beams being also adjustable laterally with respect to the intermediate beam, an upright connected with the said intermediate beam, and a scraper connected with each pair of beams, one of said pairs of beams being disposed at a higher elevation than the other pair whereby the latter may be positioned under the former when the length of the respective side beams is varied to position the one scraper in advance of the other, means for raising and lowering one of the scrapers with respect to the other when the scrapers are thus positioned, and a truck supporting one end of the beam.

In witness whereof, I hereunto subscribe my name to this specification in the presence of two witnesses.

ANVY H. MILLER.
